CLAIM

The ornamental design for an attracting plate of an electrostatic chuck for semiconductor manufacturing, as shown and described.

DESCRIPTION

FIG. 1 is a front elevational view of an attracting plate of an electrostatic chuck for semiconductor manufacturing, or the like, showing my new design;

FIG. 2 is a rear elevational view thereof;

FIG. 3 is a top plan view thereof, the bottom plan view being a mirror image of the plan view shown;

FIG. 4 is a right side elevational view thereof;

FIG. 5 is a left side elevational view thereof; and,

FIG. 6 is a bottom, rear and lower perspective view thereof.

The broken line showing in the figures is for illustrative purposes only and forms no part of the claimed design.
